UNITED STATES PATENT OFFICE.

BENJAMIN WEXLER, OF BROOKLYN, NEW YORK, ASSIGNOR TO THE PEELLE COMPANY, OF BROOKLYN, NEW YORK, A CORPORATION OF NEW YORK.

ELECTRIC INTERLOCK FOR COUNTERBALANCED ELEVATOR-DOORS.

1,328,309.

Specification of Letters Patent. Patented Jan. 20, 1920.

Application filed August 24, 1917. Serial No. 187,952.

To all whom it may concern:

Be it known that I, BENJAMIN WEXLER, a citizen of the United States, residing at the borough of Brooklyn, city of New York, county of Kings, and State of New York, have invented certain new and useful Improvements in Electric Interlocks for Counterbalanced Elevator-Doors, of which the following is a specification, reference being had therein to the accompanying drawings, which form a part thereof.

My invention relates to an electric interlock for counterbalanced elevator doors and more particularly to a type thereof wherein the power for the elevator car is under the control of the door structure so that a car cannot be started until the door is closed.

Heretofore various devices have been employed, actuated by the closing of the elevator door, to control the flow of the electric current to the motor in a manner to prevent actuation of the controller in the car resulting in the movement of said car except after the door is closed, that type of devices suitable for use with horizontal sliding doors not being adaptable for use with vertically sliding doors, and vice versa.

The object of my invention is to provide a structure embodying therein a make and break device in the electrical current for controlling the power applied to the elevator car, so arranged in the path of one of the counterbalanced sections of an elevator door as to preclude the utilization of this current for power purposes excepting when the door is in the closed position, this structure having incorporated therein means whereby said make and break mechanism can be actuated only when the door sections themselves are not only closed but are locked in relation to each other. Elevator doors made in accordance with my invention are so constructed that the electrical make and break device is under the control of, and actuated by, the elevator lock proper thus causing the interruption of the circuit, or its closing according to the type of controller used immediately upon the locking of the door sections together and preventing the closing or opening of this circuit until the doors are locked in the closed position by a mechanism operating independently of, but simultaneously with, the mechanism for controlling the electrical current.

The invention consists primarily in an electric interlock for counterbalanced elevator doors embodying therein, a plurality of vertically sliding, counterbalanced door sections having movement in opposite directions and in the same vertical plane, a latch member carried by one of said sections intermediate the sides thereof and adapted to enter a keeper upon the other door section, an electrical switch mechanism mounted in an elevator shaft adjacent and at one side of a door opening closed by, and adjacent the meeting line of, said door sections and a reciprocating plunger operatively connected with said latch member and adapted to actuate said switch mechanism when the doors are in a predetermined position, whereby the actuation of said switch is permitted only when said latch member is operative to lock said door sections in the closed position; and in such other novel features of construction and combination of parts as are hereinafter set forth and described and more particularly pointed out in the claims hereto appended.

Referring to the drawings,

Figure 1 is an elevation of a vertically movable counterbalanced door structure embodying an electric interlock embodying my invention; and

Fig. 2 is a detail fragmentary view, upon a larger scale, of the co-operating parts of said door and of said interlock.

Like letters refer to like parts in both of said views.

In the embodiment of my invention shown in the drawings, *a* and *b* indicate two sections of a vertically movable counterbalanced door structure, said sections being connected in the usual manner by means of the flexible chains or cables *c* and having movement in the same vertical plane. Said sections are guided in their movement by suitable rails or tracks *d* upon opposite sides of the door opening, with which suitable shoes *e* and *f* upon said sections respectively co-operate.

Mounted in the elevator shaft adjacent one of the tracks or rails *d* is a make and break mechanism *g* (which may be of any desired construction) included in the circuit controlling the power for actuating the elevator, in which circuit the controller upon an elevator car (not shown) is also included.

The use of such a mechanism is old and well known in the art, and a detailed description thereof is therefore unnecessary.

In the form of the invention shown, this mechanism is inclosed in a casing g' having beveled extensions g^2-g^3 at the top and at the bottom, presented toward the door opening of said casing respectively. In the side wall of the casing g' adjacent the door opening and between the extensions g^2-g^3 is an opening g^4 . A swinging arm g^5 carrying one of the contact members for the make and break mechanism is mounted within said casing and extends across this opening, with its point of pivotal support so positioned as to permit said arm to be actuated by the engagement of a plunger therewith after said plunger has passed through said opening g^4 .

The detailed construction of this make and break mechanism is immaterial to the invention; and it is capable of variation to adapt the invention to different systems of electrical control, utilizing either a normally open or a normally closed circuit. In the form of the invention shown, a normally closed circuit is used.

Carried by one of the door sections, as a , is a plunger h so mounted upon said sections as to have rectilineal movement toward and from the make and break mechanism g , a spring h' acting to normally thrust said plunger toward said mechanism into the path of the upper extension g^2 or g^3 according to which side of the door the casing g' is mounted, while the doors are moving or through the opening g^4 into operative engagement with the arm g^5 when the doors are closed. Said plunger h is slidably mounted in an elongated keeper plate h^2 housing the spring h' .

Also mounted upon the section a is a latch member i having a beveled hook i' on the lower end thereof, which hook is adapted to pass through an opening j in a plate j' , carried upon the top of the door section b . The latch member i is operatively connected with the plunger h so that said member and said plunger act in synchronism thus causing said latch member i to control the operative effect of the plunger h and its spring h' to an extent to prevent the operative engagement of said plunger with the lever g^5 unless the hook i' is passed through the opening j and has actually engaged the under side of the plate j' forming a keeper for said latch member.

In the form of the invention shown, I provide the plunger h with an extension k with which the latch member i is integrally connected and from which it projects at substantially right angles. Said extension k is mounted in a strap k' adjacent said latch member i so as to insure a substantially parallel movement of said latch member with

a longitudinal movement of the plunger h . This construction is highly desirable, in that it requires no nicety of adjustment to insure the desired quantity of relative movement of the plunger h and the latch member i since this may be controlled solely by properly proportioning the opening j . Furthermore, such a structure may be used upon either side of the door without modification of any of the parts, the extension g^3 being provided to permit the use of the same make and break mechanism on either side of the door opening.

The operation of the herein described apparatus is substantially as follows:—

When a door is in the closed position, the plunger h will be projected by the spring h' through the opening g^4 and into engagement with the arm g^5 , thus actuating the contact members of the make and break mechanism g in a manner to close the circuit and permit the application of power to the elevator car. When a car stops on any floor, and the operator desires to open the door, he merely actuates the latch member i which simultaneously withdraws the plunger h and permits the lever g^5 to spring or drop toward the opening g^4 , thus separating the electrical contacts and opening the circuit so as to prevent application of power to said car. It will be observed that the action of the operator in releasing the latch member i to permit the opening of the door, simultaneously actuates the switch mechanism controlling the circuit of the car. By reason of the rigid connection between the latch member and the plunger h , it is impossible to unlock the door without interrupting the circuit. While other connections between the latch member i and the plunger h may be used without departing from the spirit and scope of my invention, absolute reliability is secured by the mechanism shown and described without likelihood of a disarrangement of parts or of a jamming of the parts when actuating the lock and the controlling mechanism.

When the operator desires to leave a floor, before power can be applied to the car, it is essential that he close the door. It is a common practice among elevator operators to violently close doors and actuate the controller for starting the car practically simultaneously with the closing of the door. Since a certain amount of leeway in the dimension of the opening g^4 is necessary to compensate for variable conditions in the door structure, it has been found that in other types of electrical interlocks, it is possible to start the car before the door sections are actually locked, thus making it necessary to rely upon the switch casing g' as a locking means for the upper door section.

In the herein described device, however, in the event that the doors are slammed to

gether, and rebound slightly so as to prevent the hook i' passing beneath the top bar j' , the plunger h is not permitted to actuate the arm g^5 , thus preventing the application 5 of power to the car until the two vertically movable sections $a-b$ are in engagement with each other along the adjoining edges thereof and are firmly locked in this position. In this manner, I relieve the casing g 10 for the make and break mechanism and the guides d from all likelihood of stresses thereon as the result of an attempt to operate a door which is not properly locked since any such stresses in a door made in accordance 15 with my invention will be applied to the latch member i , thus relieving the plunger h therefrom.

The hook i' must pass through the opening j and under the top bar j' to permit the 20 plunger h to engage the arm g^5 , since the casing g will prevent such movement of the plunger if the hook i' be above the bar j' , and the engagement of the hook i' with the side of the opening j will prevent any outward movement of said plunger until said hook has passed completely through said opening. If inertia of the spring h' permits a rebound of the door sections before the 25 hook i' properly engages the under side of the bar j' , the various parts will be so positioned as to prevent the actuation of said arm g^5 or its equivalent. Hence, the premature starting of the car is not only prevented, but any possible variation of electrical conditions in the circuit including the controller in this car from a movement of any door 30 in a shaft from the floor side of the door opening is prevented.

In describing the operation of the device, 40 I have referred to the form of the invention shown in the drawings, although, it is not my intention to limit the invention to the details of construction herein shown and described, as such may be varied without departing from the spirit and scope of the invention.

Having described the invention what I claim as new and desire to have protected by Letters Patent is:—

50 1. An electric interlock for counterbalanced elevator doors embodying therein a plurality of vertically sliding counterbalanced door sections having movement in opposite directions and in the same vertical plane, an electrical switch mechanism mounted in an elevator shaft adjacent and at one side of a door opening closed by, and adjacent the meeting line of said door sections, a latch member carried by one of said sections 55 intermediate the sides thereof and adapted to enter a keeper upon the other door section, and a laterally reciprocatory plunger operatively connected with said latch member and adapted to actuate said switch mechanism 60 when the doors are in a predetermined posi-

tion, whereby the actuation of said switch is permitted only when said latch member is operative to lock said door sections in the closed position.

2. An electric interlock for counterbalanced elevator doors embodying therein a plurality of vertically sliding counterbalanced door sections having movement in opposite directions and in the same vertical plane, an electrical switch mechanism mounted 70 in an elevator shaft adjacent and at one side of a door opening closed by, and adjacent the meeting line of said door sections, a laterally reciprocatory plunger carried by one of said door sections adapted to actuate 75 said switch mechanism when the doors are in a predetermined position, a latch member carried by and movable with said plunger and adapted to enter a keeper upon the other door section, whereby the actuation of said switch by said plunger is permitted only when said latch member is operative to lock 80 said door sections in the closed position.

3. An electric interlock for counterbalanced elevator doors embodying therein a plurality of vertically sliding counterbalanced door sections having movement in opposite directions and in the same vertical plane, an electrical switch mechanism mounted 85 in an elevator shaft adjacent and at one side of a door opening closed by, and adjacent the meeting line of said door sections, a laterally reciprocatory plunger carried by one of said door sections and adapted to actuate said switch mechanism when the doors 90 are in a predetermined position, a latch member having a beveled hook on the lower end thereof carried by and extending at substantially right angles to said plunger and adapted to enter a keeper upon the other door section, whereby the actuation of said switch by said plunger is permitted only when said latch member is operative to lock 95 said door section in the closed position.

4. An electric interlock for counterbalanced elevator doors embodying therein a casing mounted in an elevator shaft adjacent and at one side of the door opening and having a beveled extension presenting 100 toward said door opening and an opening below said extension, an electrical make and break mechanism embodying therein a pivoted arm projecting across and adapted to normally have movement toward said opening in said casing, a plurality of vertically sliding counterbalanced door sections adapted to have movement toward and from each other, a horizontally slid able plunger mounted upon one of said sections, a spring 105 acting to normally thrust said plunger toward said casing, said plunger being adapted to engage said arm through said opening when the doors are in a predetermined position, and a latch member having 110 a beveled hook on the lower end thereof car- 115

ried by and extending at substantially right angles to said plunger and adapted to enter a keeper upon the other door section where by the actuation of said switch by said plunger is permitted only when said latch member is operative to lock said door sections in the closed position.

In witness whereof, I hereunto affix my signature in the presence of two subscribing witnesses, this 23d day of August, 1917.

BENJAMIN WEXLER.
